UNITED STATES PATENT OFFICE.

OLIVER LESLI ELLIS, OF LONDON, ENGLAND.

APPARATUS FOR HEATING AND DRYING STAVES.

SPECIFICATION forming part of Letters Patent No. 784,666, dated March 14, 1905.

Application filed August 8, 1904. Serial No. 219,916.

To all whom it may concern:

Be it known that I, OLIVER LESLI ELLIS, director of the Associated Portland Cement Manufacturers, (1900,) Limited, a subject of the King of Great Britain, residing at Dixon House, 72 Fenchurch street, in the city of London, England, have invented certain new and useful Improvements in Apparatus for Heating and Drying Staves and the Like, of which the following is a specification.

According to this invention the staves of which the cask is made, after being jointed, are passed into air or waste gases heated to a temperature of between 150° and 300° Fahrenheit. The length of time it is necessary for the staves to remain in the heated air or gases depends on their condition and the temperature of the gases; but ordinarily—that is, unless the staves are very damp—two and one-half minutes at a temperature of 250° will suffice. While the staves are still hot they are placed together and bent, so as to form them into casks.

The apparatus it is preferred to use consists of a long chamber, in or below which are one or more furnaces, whose products of combustion pass along the chamber to a chimney at its end. Above the furnace or furnaces and through the whole length of the chamber are iron plates carried on rails running longitudinally up the chamber, such rails being in turn supported by cross-girders. The iron plates extend to within about six inches of each wall of the chamber, this space being left to allow the hot gases to pass up and over the material traveling on the plates. At the furnaces the plates are carried into the wall of the chamber to protect the material from immediate contact with the fire. On these iron plates run an endless chain or chains, carried on sprocket-wheels fixed at each end of the chamber. The driving may be from either end, the sprocket-wheels at the driving end being connected by means of spur-gearings and cone-pulleys to the driving apparatus. The sprocket-wheels at the opposite end have a compensating balance and are carried on a hinged frame which is connected to a balance-

weight, thereby keeping the sprocket-chains to the required tautness. The staves are fed onto the moving sprocket chain or chains and passing through the hot gases for the whole length of the chamber are delivered at the other end. While the staves are still hot they are made up into casks. By this method the staves are uniformly dried and heated to the proper degree with certainty at a less cost than by any other known method. The casks are more durable, and when sent to a hot climate or when filled with commodities which are or may become heated the staves will not shrink and allow the contents to escape, as now frequently happens.

The drawings illustrate apparatus made in accordance with this invention.

Figure 1 is a side elevation, and Fig. 2 a plan, partly in section. Fig. 3 is a transverse section on the line A A, Fig. 1, and Fig. 4 a similar section on the line B B to a larger scale.

a is the long chamber, and *b b b* the furnaces whose products of combustion pass along it to the chimney *c*. (Shown in Fig. 2.)

d represents the iron plates supported on rails *e*, which in turn are supported by transverse rails *f*, which plates extend across the whole width of the chamber at the furnaces, but leaves spaces *g* between their edges and the walls of the chamber for the remainder of their extent.

h h are the chains passing over sprocket-wheels *i i* and *j j* at each end of the chamber *a*, the sprocket-wheels *i i* being driven by spur-gearing *k* through cone-pulleys *l*. The sprocket-wheels *j j* are carried by a hinged frame *m*, which is connected to a weight *n*, thereby keeping the sprocket-chains to the required tautness.

The endless chains *h h* move above the plates *d* and return through the flue *o*, passing through holes *p p* in the side walls of the furnaces.

I do not herein claim the process of treating staves, consisting in jointing the staves, passing them into gases heated to a temperature of between 150° and 300° Fahrenheit, and then while hot forming them into a cask, as

such a claim is made in my application for patent, Serial No. 240,934, filed January 13, 1905.

I claim—

- 5 1. Apparatus for drying staves consisting of a long chamber, a furnace whose products of combustion pass along the chamber, a plate running longitudinally up the chamber of less width than the chamber except where it passes above the furnace, an endless chain passing over the plate, and means for actuating the chain.
- 10 2. Apparatus for drying staves consisting of a long chamber, a furnace whose products of combustion pass along the chamber, a plate running longitudinally up the chamber of less width than the chamber, except where it passes
- 15

above the furnace; an endless chain passing over the plate, sprocket-wheels at each end of the chamber engaging the chain, and means 20 for turning the sprocket-wheels.

3. Apparatus for drying staves consisting of a long chamber, furnaces whose products of combustion pass along the chamber, a plate running longitudinally up the chamber of less width than the chamber except where it passes above the furnaces, endless chains passing over the plate, sprocket-wheels at each end of the chamber engaging the chains, and means for turning the sprocket-wheels.

OLIVER LESLI ELLIS.
